NEEDLE HOLDING MEANS FOR HYPO-DERMIC NEEDLE HONING DEVICES OR THE LIKE

Ernest R. Post, Washington, D. C.

Application November 1, 1948, Serial No. 57,748

1 Claim. (Cl. 51—157)

1

This invention relates to quick-release chuck means for firmly gripping a shank, and more specifically to such means for use in a needle holder for a hypodermic needle honing device. To furnish an illustrative background for this chuck means, the honing device will be briefly described in this specification.

The object of the present invention is to construct a quick-release chuck means for the hypodermic needle holder or honing device, which will hold the needle shank firmly in any rotational and axial adjustment in the central opening of the holder through which the needle is inserted, to maintain it in proper honing position.

Another object is to make a quick-release chuck means comprising a body portion having a central passage for insertion of a needle, a series of annularly spaced, radially slidable and outwardly resiliently biased members in said body portion, radially inwardly wedging means for said members to grip said needle shank firmly, and manually operated means for moving said wedging means in one direction to cause said members to grip said shank, and in the other direction to release it.

Another object is to make the above chuck with the needle gripping members, equi-angularly spaced and having springs for normally biasing them outwardly.

Another object is to construct the above chuck means with a ring having internal cam portions providing the wedging action against the outer ends of said three needle gripping members when the ring is turned in one direction through less than 120°, and releasing the needle when the ring is turned back.

Another object is to provide a projecting lug on said ring to serve as a knob or handle for easier actuation of the ring with the fingers.

Another object is to provide means in the holder for fixing the chuck means in any rotational position, so as to place the projecting lug in a convenient operating range.

Other and more specific objects will appear in the following detailed description, having reference to the accompanying drawings, wherein:

Figure 1 is a front elevational view of a hypodermic needle honing device with the quick-release chuck means for holding a needle in position to be honed.

Figure 2 is a transverse section taken on the lines 2—2 of Figure 1, and

Figure 3 is a longitudinal section taken through the quick release chuck means for gripping the needle to be honed.

Briefly described, the needle honing device with which the quick-release chuck is associated, includes a plastic base board 1, a base 2 of metal with chrome plating and the rest of the parts

2

are also of chrome-plated metal, except the hone 3.

The hone 3 is oval in section and is held in close-fitting sockets in bearings 4 and 5 at its ends rotatably mounted in supports 6 and 7 respectively. The bearing 4 is provided with mechanism to effect rotation of the hone 3 and is operated by the knob 11.

A shaft 13 is mounted in smaller supports 14 and 15 so as to extend in a direction parallel to the hone 3. A needle holder consisting of a quick-release clutch means includes a circular ring-like frame 17 with a circular bore therein and a lower widened portion having a bore to receive the shaft 13 and upon which the ring-like frame is slidably mounted. A stepped annular body designated in general by the reference character 16 has a radially reduced outer portion rotatably mounted in the circular bore of the ring-like frame for rotational adjustment therein. The opposite or inner side of the annular body 16 is annularly enlarged and forms an outwardly facing annular circumscribing radial shoulder 16^a that is disposed against the inner side or annular face of the frame 17 as clearly shown in Figure 2. A set screw 18 is radially threaded through the top of the frame 17 to engage the periphery of the reduced outer portion of the annular body 16 for holding the latter in adjusted position. The enlarged inner end of the body 16 carries an outwardly directed and integral annular flange 16^b. The annular body 16 has an axial opening 19 therein for insertion of the hypodermic needle 20 to be sharpened. The opening 19 is normal to and spaced from the shaft 13 a distance substantially equal to the difference in height between the shaft and hone.

The body portion 16 also has three radially slidable equi-angularly spaced gripping members 21 about the opening 19. A ring 22 is mounted rotatably on the enlarged portion of the annular body between and in contact with the adjacent side of the ring-like frame 17 and the flange 16^b as shown and which mounting is operative to eliminate any undue wobbling or vibratory movements of the ring 22 during the use of the needle honing device, and has three internal wedging cams 23 for cooperation with the outer ends of said gripping members to push them inwardly simultaneously to grip the needle shank firmly, upon turning the ring 22 in one direction, and releasing it when the ring is turned in reverse direction. Springs 24 are provided in the body portion 16 for biasing said gripping members 21 radially outwardly against their respective cams 23.

The ring 22 is provided with a short knob 25, extending from the periphery thereof, to facilitate turning the ring with the fingers in

one direction or the other. By releasing the set screw 18, the body portion 16 may be turned to any angular position to provide the range of movement of the knob 25 in any suitable location about said needle holder.

The chuck specifically described and claimed herein has been illustrated as holding a hypodermic needle for the honing thereof, but it is to be understood that while the chuck may be constructed for the holding of work of larger dimensions, it was primarily designed for the holding of small shanked elements. The chuck instead of being slidably mounted as illustrated, may be mounted on a stationary support or form an element of a lathe, and it is understood that the use of this chuck may reach into various arts where a quick release chucking means is desired for use.

Obviously modifications in the form and arrangement of parts may be made without departing from the spirit or scope of this invention, as defined in the appended claim.

What is claimed is:

A needle holding device of the class described comprising a circular ring-like frame having a circular bore and a lower widened portion with a bore therein, a shaft engaged through the bore of the lower widened portion to slidably support the frame, a stepped annular body having a radially reduced outer portion rotatably mounted in the circular bore for rotational adjustment and an enlarged inner portion forming an outwardly facing annular circumscribing radial shoulder disposed against the inner portion of the inner annular face of the frame, a set screw radially threaded through the top of the frame to engage the periphery of the reduced outer portion of the body and hold the latter in adjusted position, the inner end of the body having an integral annular radial flange, a ring rotatably mounted on the enlarged inner portion

of the body between and in contact with the frame and flange, said ring having a plurality of successive tapered, arcuate recesses around its inner face forming wedging cams, a similar number of equidistantly spaced radial gripping pins slidably mounted in radial bores in the enlarged portion of the body with convex outer ends conforming to the inner faces of the recesses and reduced tapered inner ends slidable in reduced inner portions of said radial bores and forming inwardly facing shoulders, said radial bores having annular outwardly facing shoulders therein at the outer ends of the reduced portions thereof, springs on said reduced portions between said inwardly and outward-facing shoulders to force the pins against said cams, and a radial knob on the ring periphery to turn the ring in a limited arc in opposite directions with the rotational range allowed by the rotational adjustment and fixing of the body in the circular bore of the frame by the set screw to vary the gripping action of the tapered pins against the needle when the ring is turned in one direction and to release the same in the opposite direction.
